UNITED STATES PATENT OFFICE.

WILLIAM E. BAUER, OF CHICAGO, ILLINOIS.

WOOD-TRIMMER.

1,334,070.

Specification of Letters Patent. Patented Mar. 16, 1920.

Application filed July 18, 1919. Serial No. 311,832.

To all whom it may concern:

Be it known that I, WILLIAM E. BAUER, a citizen of the United States, residing at Chicago, in the county of Cook and State of Illinois, have invented a certain new and useful Improvement in Wood-Trimmers, of which the following is a full, clear, concise, and exact description, reference being had to the accompanying drawings, forming a part of this specification.

My invention relates to wood trimmers, and briefly stated, its object is to provide a revolving knife wood trimmer for general use in trimming all kinds and grades of wood. The device of my invention is particularly adaptable for use in trimming pieces of wood that are to be fitted together by fine mitered-joints, but its use is manifestly not so limited, as the device is capable of being used by workers in wood and other similar materials for practically all purposes where accurate trimming is necessary or desirable.

My invention contemplates the provision of a device of this class that may be economically manufactured, that is rugged in its construction, and one that is capable of performing its intended function with a minimum amount of effort on the part of the operator.

Perhaps the most salient features of the device of my invention reside in the cutting knife, and means for operating the knife so that in the operation of the trimmer the knife is not only moved against and through the wood being trimmed, but simultaneously with such movement has imparted to it, a rotary movement. In other words, in the operation of the trimmer, the knife is simultaneously rotated and moved in a line at right angles to the axis of rotation, whereby a slicing cut is effected.

These and other features of my invention are fully set forth in the following description, wherein reference is made to the accompanying drawing in which—

Figure 1 is a front elevational view of a wood trimmer constructed in accordance with my invention, portions of certain parts being broken away more clearly to reveal the construction and disposition of other parts therebehind.

Fig. 2 is a top plan view of the wood trimmer.

Fig. 3 is a vertical sectional view taken on the line 3—3 of Figs. 1 and 2, and

Fig. 4 is a fragmentary sectional view taken on the line 4—4 of Fig. 3.

Similar characters of reference refer to similar parts throughout the several views.

The wood trimmer comprises a base 5 provided with suitable legs 6 which are preferably apertured to facilitate mounting the device on a bench or other support. Disposed at opposite ends of the base 5 and adjacent one side thereof are pillars 7—7 conveniently secured to the base by bolts 8—8. The pillars support and are preferably formed integral with the bridge 9 which lies above the base and parallel therewith, and mounted on the base is a pair of guides 10—10 for the wood to be trimmed, each of said guides being provided with a bolt and wing nut 11 whereby the guides may be secured in a multiplicity of positions with respect to the base. The free vertical edge of each guide lies against one of the pillars 7, and of course is held firmly against the latter when a piece of wood is placed on the base and pressed against the guide 80 preparatory to the trimming operation. If desired, a multiplicity of lines 12—12 may be made to appear on the upper surface of the base to enable the workman accurately to adjust the guides at certain definite positions corresponding to cuts of certain angularity.

As is most clearly shown in Fig. 3, oppositely disposed and parallel grooves 13 and 14 are formed in the base 5 and bridge 9 respectively. At 15 is illustrated a reciprocating carriage or cross-head, which at its upper and lower edges is provided with longitudinal ribs conformed to have a sliding fit in the grooves 13 and 14. Cast integral with the base and lying parallel with the forward edge thereof is a bar 16 provided with a depressed rack 17 which lies parallel with and directly beneath a similar but longer depressed rack 18 formed in an overhanging portion of the carriage or cross-head 15. Disposed between the racks 17 and 18 and meshing with both is a spur gear 20 which is retained in posi-

tion solely by the sides of the depressed racks. Said gear is provided with an integral hub 21 to which is attached an upwardly projecting operating handle 22, said attachment of handle and hub conveniently being accomplished by securing the former in a radial slot in the latter by a screw 23.

At 24 is illustrated a spur gear having an integral stub shaft 25 which is journaled in 10 the reciprocating carriage or cross-head 15, as is most clearly illustrated in Fig. 2. Removably supported by said gear 24 is the rotary knife or cutting disk illustrated at 26. Said knife is attached to gear 24 by a plurality of screws 27-27. Rotatably supported by the carriage or cross-head and retained in position by screw and nut indicated at 15 28 is a pinion 29; said pinion meshing with gear 24 and with a rack 30 formed on the 20 under side of the stationary bridge 9.

It will be noted that the base is provided with an elongated slot 31 in which is received the lower edge of the knife 26, the 25 said slot serving to permit the knife to travel with the carriage as the latter is reciprocated. Attention is directed to the fact that an elongated slot 32 is formed in the stationary bridge 9 to permit removal and replacement of the knife without disassembling the other parts of the mechanism. The base on its under side is provided with the hollow rib 33 which serves to house that portion of the knife which projects through the slot 31. I prefer that the bottom of 35 the rib should be provided with an insert 34 of rubber or other yielding material, so that upon insertion of the knife the cutting edge of the latter may not come directly into contact with a hard, unyielding object.

40 In the use of the trimming tool, the wood upon which the work is to be performed is placed upon the base 5 and pressed against one of the guides, which of course has been given the proper angular adjustment. The 45 handle 22 is then grasped and moved in the proper direction to cause the knife to be moved toward and against the wood to be trimmed. The movement of handle 22 causes gear 20 to move along stationary rack 50 17, and since said gear 20 meshes with rack 18 of the reciprocating carriage, the latter is caused to traverse a distance twice that which the gear 20 travels along stationary rack 17. While the carriage is being moved 55 as just explained, the pinion 29, due to its meshing engagement with the rack 30 and the stationary bridge 9, is rotated, and since the pinion 29 meshes with the gear 24, the latter is rotated and with it the knife 26, 60 causing the latter to effect a downwardly directed slicing or shearing cut upon the wood against and through which it is carried by the reciprocating carriage.

It will of course be understood that handle 22 may be operated to cause the knife

to act upon wood placed against either of the guides 10-10. The operation is the same in both cases. It is desirable to have two guides and a knife capable of acting upon wood placed against either of them, since this arrangement renders it possible more or less permanently to set one of the guides at the most frequently used position, say for instance for a 45° cut, using the other guide for the more infrequent adjustments.

At 24 is illustrated a spur gear having an integral stub shaft 25 which is journaled in 10 the reciprocating carriage or cross-head 15, as is most clearly illustrated in Fig. 2. Removably supported by said gear 24 is the rotary knife or cutting disk illustrated at 26. Said knife is attached to gear 24 by a plurality of screws 27-27. Rotatably supported by the carriage or cross-head and retained in position by screw and nut indicated at 15 28 is a pinion 29; said pinion meshing with gear 24 and with a rack 30 formed on the 20 under side of the stationary bridge 9.

It will be noted that the base is provided with an elongated slot 31 in which is received the lower edge of the knife 26, the 25 said slot serving to permit the knife to travel with the carriage as the latter is reciprocated. Attention is directed to the fact that an elongated slot 32 is formed in the stationary bridge 9 to permit removal and replacement of the knife without disassembling the other parts of the mechanism. The base on its under side is provided with the hollow rib 33 which serves to house that portion of the knife which projects through the slot 31. I prefer that the bottom of 35 the rib should be provided with an insert 34 of rubber or other yielding material, so that upon insertion of the knife the cutting edge of the latter may not come directly into contact with a hard, unyielding object.

40 In the use of the trimming tool, the wood upon which the work is to be performed is placed upon the base 5 and pressed against one of the guides, which of course has been given the proper angular adjustment. The 45 handle 22 is then grasped and moved in the proper direction to cause the knife to be moved toward and against the wood to be trimmed. The movement of handle 22 causes gear 20 to move along stationary rack 50 17, and since said gear 20 meshes with rack 18 of the reciprocating carriage, the latter is caused to traverse a distance twice that which the gear 20 travels along stationary rack 17. While the carriage is being moved 55 as just explained, the pinion 29, due to its meshing engagement with the rack 30 and the stationary bridge 9, is rotated, and since the pinion 29 meshes with the gear 24, the latter is rotated and with it the knife 26, 60 causing the latter to effect a downwardly directed slicing or shearing cut upon the wood against and through which it is carried by the reciprocating carriage.

It will be understood that by virtue of the herein described mechanism between the handle and the rotating and reciprocating knife, the power applied by the workman at the handle 22 is so utilized as to afford the advantage of a powerful lever, thus rendering it possible neatly to trim woods of very hard and tough nature with comparative ease. Regardless of the direction in which the carriage is moved when the knife engages the wood, the latter always effects a downwardly directed slicing cut, which is most effective.

While in this specification and in the appended claims I have referred to the device of my invention as a wood trimmer, it will be understood that the device may be used for cutting various materials other than wood. The device is primarily a wood trimmer, but its use for other purposes is of course clearly within the scope of my invention.

While I have illustrated one embodiment of my invention, which at the present time I consider to be a preferred form thereof, I do not limit myself to the construction shown, but claim all equivalent constructions coming within the terms and spirit of the appended claims.

Having thus described my invention, what I claim is new and desire to secure by Letters Patent of the United States is:

1. A wood trimmer comprising a support for the wood to be trimmed, a stationary rack, a reciprocating carriage provided with a rack spaced from and parallel with said first rack, a gear disposed between said racks and meshing with both, a handle attached to said gear adapted to cause the latter to travel along said first rack and simultaneously reciprocate said carriage, a rotary knife carried by said carriage and arranged to reciprocate therewith, a third and stationary rack, a gear fixed with respect to said rotary knife, and a pinion carried by said carriage meshing with said third rack and said last mentioned gear, whereby said knife is rotated concurrently with its reciprocation.

2. A wood trimmer comprising a support for the wood to be trimmed, a stationary rack, a reciprocating carriage carrying a rack spaced from and parallel with said first rack, a gear disposed between said racks and meshing with both, means for causing said

gear to travel along said first rack, a rotary knife carried by said carriage, said knife adapted to reciprocate with said carriage, and means arranged to rotate said knife concurrently with its reciprocation.

3. A wood trimmer comprising a support for the wood to be trimmed, a stationary depressed rack, a reciprocating carriage carrying a second depressed rack spaced from and 10 parallel with said first rack, a gear disposed between said racks and meshing with both, said gear held in position solely by its engagement with said depressed racks, means for causing said gear to travel along said 15 first rack, a rotary knife carried by said carriage, said knife adapted to reciprocate with said carriage, and means arranged to rotate said knife concurrently with its reciprocation.

20 4. A wood trimmer comprising a support for the wood to be trimmed, a stationary rack, a reciprocating carriage, a second rack carried by said carriage, said racks being disposed parallel with each other, a gear freely 25 disposed between said racks and meshing with both, means for causing said gear to travel along said stationary rack and thereby reciprocate said carriage, a rotary knife carried by said carriage and arranged to reciprocate therewith, and means actuated by 30 the reciprocation of said carriage arranged to rotate said knife concurrently with its reciprocation.

5. A wood trimmer comprising a support 35 for the wood to be trimmed, a stationary rack, a reciprocating carriage, a second rack carried by said carriage, said racks being disposed parallel with each other, a gear freely disposed between said racks and meshing with both, means for causing said gear to travel along said stationary rack and thereby reciprocate said carriage, a rotary knife carried by said carriage and arranged to reciprocate therewith, and means actuated by 40 the reciprocation of said carriage, arranged to rotate said knife in a direction to effect a downwardly directed slicing cut 45 upon the wood carried on said support.

6. A wood trimmer comprising a stationary element and a reciprocating element, one of said elements being provided with a support for the wood to be trimmed, a rotary knife carried by the other element, a rack carried by the stationary element, a rack 50 carried by the reciprocating element, said racks being spaced apart and parallel to each other with their teeth projecting in opposite directions, a gear freely disposed between said racks and meshing with both, means for 55 causing said gear to travel along the rack carried by the stationary element, and there-

by actuate the reciprocating element, together with means actuated by the movement of said reciprocating element for rotating said knife.

65

7. A wood trimmer comprising a stationary element and a reciprocating element, one of said elements being provided with a support for the wood to be trimmed, a rotary knife carried by the other element, a rack carried by the stationary element, a rack carried by the reciprocating element, said racks being spaced apart and parallel to each other with their teeth projecting in opposite directions, the spaces between the 70 teeth of said racks being closed on each side thereof, a gear freely disposed between said racks and meshing with both, said gear being retained in position solely by its engagement with said racks, means for causing said 75 gear to travel along the rack carried by the stationary element and thereby actuate the reciprocating element, together with means actuated by the movement of said reciprocating element for rotating said knife.

80

8. A wood trimming tool comprising a base, a stationary rack carried by said base, a carriage mounted for reciprocation relative to said base, a rack carried by said carriage disposed parallel with and spaced from the first rack, a gear freely disposed between 90 said racks and meshing with both, means for turning said gear, a knife rotatably supported by said carriage, a gear fixed to said knife, a pinion rotatably supported by said carriage, said pinion meshing with said last mentioned gear, and a stationary rack meshing with said pinion whereby said knife is 95 rotated when the carriage is reciprocated.

9. A wood trimming tool comprising a horizontal support, pillars rising from said support, a bridge carried by said pillars, a reciprocating carriage mounted between said bridge and said support, a stationary rack carried by said support, a rack carried 100 by said carriage overhanging said first rack, a gear disposed between said racks and meshing with both, means for turning said gear, a rotary knife carried by said carriage, a gear fixed with respect to said knife, a 105 pinion rotatably supported by the carriage and meshing with said last mentioned gear, and a rack formed on said bridge with which said pinion meshes whereby the knife is rotated when the carriage is reciprocated.

115

In witness whereof, I hereunto subscribe my name this 14th day of July, 1919.

WILLIAM E. BAUER.
